UNITED STATES PATENT OFFICE.

ANDREAS SENDLEIN, OF ST. LOUIS, MISSOURI.

MOLDING AND COMPRESSING MACHINE.

SPECIFICATION forming part of Letters Patent No. 711,883, dated October 21, 1902.

Application filed March 15, 1902. Serial No. 98,417. (No model.)

To all whom it may concern:

Be it known that I, ANDREAS SENDLEIN, a citizen of the United States, residing at St. Louis, State of Missouri, have invented certain new and useful Improvements in Molding and Compressing Machines, of which the following is a full, clear, and exact description, reference being had to the accompanying drawings, forming a part hereof.

10 My invention has relation to improvements in molding and compressing machines; and it consists in the novel arrangement and combination of parts more fully set forth in the specification and pointed out in the claims.

15 In the drawings, Figure 1 is a front elevation of the machine. Fig. 2 is a rear elevation thereof. Fig. 3 is an elevation of one side thereof. Fig. 4 is an elevation of the opposite side. Fig. 5 is a part-sectional elevation showing the cams operating the compressing-plungers. Fig. 6 is a part-sectional elevation showing the cams operating the ejecting device, the feed-head, and the male portion or tongue of the die. Fig. 7 is an enlarged sectional front elevation showing the die and co-operating parts. Fig. 8 is a view at right angles to Fig. 7. Fig. 9 is a horizontal section on line 9 9 of Fig. 7. Fig. 10 is a sectional enlarged detail (corresponding to 20 the parts as shown,) showing the cut-off piston and the feed-head. Fig. 11 is a horizontal section on line 11 11 of Fig. 10. Fig. 12 is an elevation in detail showing cam operating the cut-off piston, the latter corresponding to its position in Fig. 3. Fig. 13 is a similar view showing the cut-off piston elevated and the feed-head withdrawn, this position corresponding to that occupied by the parts in Fig. 6. Fig. 14 is a sectional detail 25 showing the material operated on in the act of compression in the die and the feed-head withdrawn. Fig. 15 is a sectional detail on line 15 15 of Fig. 6. Fig. 16 is a section on line 16 16 of Fig. 6. Fig. 17 is a vertical section on line 17 17 of Fig. 3. Fig. 18 is a transverse section on line 18 18 of Fig. 7. Fig. 19 is a section on line 19 19 of Fig. 5. Fig. 20 is a view of the reverse face of the cam-disk shown in Fig. 6, illustrating the 30 cam-surface which actuates the feed-head; and Fig. 21 is a detail showing the last position occupied by the component parts of the

die previous to the removal of the compressed block by the ejector.

The present invention relates to a class of 55 machines designed for molding and compressing into blocks suitable composition for use as a fire-kindler, the particular object of the invention here described being to produce a machine which shall operate on a 60 maximum number of blocks, one the product of which shall be uniform, one which shall be compact and positive, one which is simple in construction, one producing blocks of great compactness, one which is positive in 65 action, and one possessing further and other advantages, better apparent from a detailed description of the invention, which is as follows:

Referring to the drawings, F represents a 70 suitable machine-frame of any approved design, the same supporting in suitable bearings the drive-shaft S, having at one end a belt-pulley P, driven from any suitable source of power. (Not shown.) Mounted on said shaft 75 is a pinion 1, which meshes with a gear-wheel 2 on a parallel shaft S'. The latter is provided with a smaller gear-wheel 3, meshing with a gear-disk 4, mounted on shaft S" on the upper section F' of the machine-frame. 80 The arrows in Fig. 4 represent the relative direction of rotation of the several parts, as described. Carried also by the main shaft S is a belt-pulley 5, from which passes a belt 6 over the terminal pulley 7 of a spiral conveyor or screw 8, mounted on the base of the trough 9, carried by the standards 10 10 on top of the machine-frame. A suitable tightening pulley or idler 11 is provided for the belt 6, as usual in this class of machines. 85 The composition or material from which the fire-kindlers or fuel-blocks are to be formed is fed into the trough 9 from any convenient source, (not shown,) the screw conveyor 8 carrying the material forward until the same 90 comes opposite the opening 12, formed in the trough, where it drops, partially to the bottom of the feed-head receptacle 13 and partially on top of the cut-off piston 14, Figs. 5, 10, where the feed-head 15 shoves it into the space 100 formed between the inner male member or tongue 16 of the die and the outer enveloping female member or plunger 17, the compression of the material being finally effected by

the approach of the plunger 17 and coöperating plunger 18 around the tongue 16, the result being a hollow fuel-block B, Fig. 21.

The manner of molding and compressing the block B, the manner of expressing from it any excess of water, moisture, or liquid hydrocarbons which enter into its composition, and the manner of ejecting the block when completed are all accomplished by a series of cams, which are themselves actuated by the driving power of the machine, and while systems of cams are in themselves not new in machines of this class, my present arrangement contemplates a compactness and simplicity of structure and positiveness of action not attained in the majority of machines of this type.

The gear-disk 4 has formed thereon a cam-track *a*, having concentric portions *a'* *a''*, traversed by the pin (or roller) 19 at one end of a bent lever 20, pivoted to a bracket 21, the opposite end of the lever being pivotally connected to the lower end of a link 22, whose upper end is hinged to the free end of an arm 23, carried at one end of a rock-shaft 24, mounted on top of the bracket 25. The opposite end of the rock-shaft 24 carries an arm 26, which in turn is pivotally coupled to the lower end of a link 27, whose opposite end is 30 hinged to one member of a bell-crank lever 28, mounted on top of the standards 10 10, the opposite member of the bell-crank being pivotally coupled to a link 29, which is in turn connected to the plunger 18, previously referred to. It is obvious from the foregoing that with the rotation of the gear-disk 4 in the direction as indicated the cam-track will cause the plunger 18 to reciprocate up and down and assume first one and then the other of its extreme positions, Figs. 5, 8, it being temporarily at rest while the pin 19 is traversing the concentric portions *a'* *a''*. Coöperating with the plunger 18 is the plunger 17 and tongue 16, since by their combined action the block B results. The base of the plunger 17 is coupled to a link 30, which connects it to one end of a weighted lever 31, mounted on a fulcrum-rod 32, the former being provided on opposite faces with pins 33, traversing the 45 cam-tracks *b* and their concentric portions *b'* on the cam-disks 34, mounted on the shaft S'. Rotating as the disks 34 do in the direction of the arrow, Fig. 5, they gradually constrain the pins 33 to move toward the center of the 50 disks, and thus force the plunger 17 upward to the position indicated in Fig. 5. By the time the pins 33 have reached the points *x* of their respective cams the plunger will have imparted thereto a final movement upward, 55 (at which instant the plunger 18 has begun its receding or upward movement,) this final movement raising the block B to a plane on a level with the ledge L, by which the block is received, Fig. 21.

60 The tongue 16, by which the opening in the fuel-block B is formed, is operated as follows: The base of the tongue carries a collar 35,

connected thereto by pins 36 36, which pass through longitudinal slots 37 37, formed in the opposite walls of the plunger 17, to allow 70 for the necessary reciprocation between the parts. The remaining two sides of the collar are provided with arms or elongated pins 38 38, which project through the sinuous longitudinal slots 39 39 of the standards 10 10, the outer projecting end of one arm 38 being pivotally connected through a link 38' to one end of a balance-lever 40, mounted on the rod 32, the outer projecting end of the other arm being connected through a link 38'' to one end 80 of a lever 40', mounted on the same rod 32, the opposite end of said lever 40' being provided with a pin 41, traversing the cam-track *c* and its concentric portion *c'* of the disk 42, mounted on the shaft S', Figs. 4 and 6. During the passage of the pin (or roller) 41 along the concentric portion *c'* of the track *cc'* there is sufficient play allowed for the lever 40' to permit the plunger 17 to carry the tongue 16 with it while the former makes its final movement in raising the block B to the level of the ledge L, as previously described. In this final movement a tappet or peg 42 on the collar 35 strikes the lower end of the stem 43 of a valve 44, normally plugging the end of the 95 cut-off piston 14, Fig. 10, allowing the water and other fluids expressed from the block to drain and be discharged from the machine, the valve being subsequently seated by the coiled spring 45, confined between the guide-lugs 46 46, one end of the spring being connected to said stem. The opening of the valve 44 of course takes place after the formation of the block and its elevation to the plane indicated in Fig. 21 and after the cut-off piston has been elevated to a position to form a retaining-wall for the block during its compression, Figs. 5, 14, and of course after the feed-head has been retracted to a position to begin the next feed operation, Fig. 5. During the feed operation the cut-off piston occupies its lowest position, Fig. 8, it being reciprocated between these two limits by the following mechanism: The cut-off piston is hollow, having confined therein a pivoted link 110 47, whose lower end is pivotally coupled to a balance-lever 48, having an arm 49 rigidly secured thereto, the free end of the latter having a terminal pin 50 traversing the cam-track *d*, and its concentric portion *d'* of the cam-disk 51 115 mounted on shaft S''. When the parts thus far described occupy the position shown in Figs. 8, 10, the feed-head 15 feeds the material into the die, as indicated in Figs. 7 and 8, the composition first striking the pyramidal apex 120 16' of the tongue, being subsequently well shaken down into the space around the tongue by the vibratory motion imparted to the latter during its reciprocations along the sinuous slots 39, previously referred to. The reciprocation of the feed-head is accomplished as follows: The latter has pivotally secured thereto a stem 51', whose opposite end is coupled to one arm of a lever 52, pivoted to a stud or

boss 53 on a bracket 54, the opposite arm of the lever having a pin 55 traversing the cam-track *e e'* on one face of the cam-disk 56, mounted on the shaft *S'*. The opposite face 5 of the disk 56 is provided with a cam-track *f f'*, traversed by a pin 57 at the end of one arm of a lever 58, rocking about a stud 59 on a bracket 60, the free end of the opposite arm being pivotally coupled to the adjacent end 10 of a link 61, passing through lugs 62, the opposite end of the link 61 being connected to an arm 63, projecting laterally from the cross-bar of the adjacent end of the ejecting-frame 64, the latter being in the nature of an oblong 15 frame, Fig. 9, one end of which in its retraction or outward movement comes in contact with the block *B* when fully elevated, drawing the latter after it and depositing it on the ledge *L*, Fig. 21. The lateral bars of the frame 20 64 are guided in suitable grooves or ways 65, formed in the standards 10 10.

It will be observed that the series of cam-tracks by which the movements to the several parts are imparted are composite in their nature, having portions both eccentric to and concentric with the axes of rotation of the disks on which the cam-tracks are disposed. 25 During the passage of any lever over the concentric portion of any cam-track no motion results to the parts connected to such lever, and the several cams are so set relatively to one another and so proportioned that for any period of rest of those parts actuated by one cam the parts connected to other cams are 30 being actuated, and vice versa. Thus, for example, while the cut-off piston occupies the position shown in Fig. 10 during the brief interval that the arm 49 is traversing a concentric portion of its cam-track the feed-head is 35 operating, and during the interval that the same cut-off is in the position shown in Figs. 13, 14 the cams are actuating the pistons 17 18 and tongue 16, and so on, as clearly obvious from the foregoing to those skilled in 40 the art.

While I do not wish to be limited to the particular curvatures of cam-tracks here shown, I have found that the forms illustrated give 45 very superior results both in the matter of rapid compression of the blocks and reduction of the friction incident to machines of this type. It is further apparent that I may depart in minor details of construction without in any wise affecting the nature or spirit of 50 my invention.

Having described my invention, what I claim is—

1. In a press, a suitable trough, a conveyer located therein, a die comprising a reciprocating tongue, an enveloping reciprocating plunger, and a second reciprocating plunger coöperating with the enveloping plunger, the latter being adapted to receive the contents of the trough, substantially as set forth.

65 2. In a press, a suitable trough, a conveyer located therein, a die adapted to receive the material fed to the trough, said die being com-

posed of an outer enveloping plunger, an inner tongue reciprocating therein, means for imparting a vibratory motion to the tongue 70 during its reciprocating movements, and a second hollow plunger adapted to pass about the tongue and coöperate with the first-named plunger, substantially as set forth.

3. In a press, a suitable trough, a conveyer 75 located therein, a feed-head receptacle mounted below the trough, a cut-off piston normally occupying a position on a level with the base of the receptacle, a hollow plunger, a tongue confined within the same, a second hollow 80 plunger coöperating with the first hollow plunger and likewise adapted to pass about the tongue, the latter having an apex or point adapted to direct the material delivered from the feed-head receptacle, to the space between 85 the tongue and its enveloping plunger, suitable cams for actuating the several plungers, the cut-off piston, and feed-head, and means for imparting a vibratory movement to the tongue during its reciprocations, substantially 90 as set forth.

4. In a press, a suitable hollow plunger, standards confining said plunger, a tongue located within said plunger, a collar at the base of the tongue, slots formed in two of the 95 walls of the plunger, pins projecting from the tongue and operating in said slots, sinuous slots formed in the walls of the standards, arms projecting from the collar and operating in said sinuous slots, a second hollow plunger 100 coöperating with the first hollow plunger, a feed-head for delivering the material into the die, a cut-off piston forming a wall for the material during the molding and compressing of the same, and suitable cams for 105 actuating the several parts, substantially as set forth.

5. In a press, a die composed of a tongue, an enveloping plunger for the same, and a second hollow plunger coöperating with the 110 enveloping plunger, means for reciprocating the plungers, and means for imparting a vibratory movement to the tongue, substantially as set forth.

6. In a press, a suitable trough, a conveyer 115 for removing the material therefrom, a feed-head receptacle for receiving said material, a hollow plunger located adjacent to the receptacle, a tongue confined in said plunger, a cut-off piston adapted to cut off the material delivered from the feed-head receptacle, a spring-controlled drain-valve carried by the cut-off piston, and means interposed between the tongue and valve for actuating the latter, substantially as set forth.

7. In a press, a hollow cut-off piston, a drain-valve normally closing the bottom of the same, a stem for said valve, a spring encircling said stem and forcing the valve to its seat, a die composed of a hollow plunger and inner 130 tongue and a second coöperating plunger, and a tappet coupled to the tongue adapted to trip the stem and unseat the valve, substantially as set forth.

8. In a press, a suitable feed-head receptacle, a depositing-ledge located opposite thereto, a die located between the ledge and receptacle, said die being composed of an inner reciprocating tongue, an enveloping reciprocating plunger therefor, and a second hollow reciprocating plunger coöoperating with said tongue and enveloping plunger, means for feeding the material from the receptacle to the die, means for actuating the die and molding the material into blocks, the enveloping plunger being adapted for elevating the blocks to the level of the depositing-ledge, and suitable ejecting devices for depositing the blocks on the ledge, substantially as set forth.

9. In a press, a suitable die composed of an inner reciprocating tongue, an enveloping reciprocating plunger therefor, a second hollow

reciprocating plunger coöoperating with said tongue and enveloping plunger, standards for confining said die, an ejector comprising a hollow reciprocating frame, guideways formed in the standards for the travel of said frame, a ledge for receiving the molded blocks, and suitable cams for actuating the ejector, substantially as set forth.

10. In a press, a die having a reciprocating tongue, and means for vibrating said tongue during its reciprocations, substantially as set forth.

In testimony whereof I affix my signature in presence of two witnesses.

ANDREAS SENDLEIN.
